UNITED STATES PATENT OFFICE.

SIMPSON B. DYER, OF TULIA, TEXAS.

DISPLAY-STAND.

1,195,795.

Specification of Letters Patent. Patented Aug. 22, 1916.

Application filed May 6, 1913. Serial No. 765,911.

To all whom it may concern:

Be it known that I, SIMPSON B. DYER, a citizen of the United States, residing at Tulia, in the county of Swisher and State 5 of Texas, have invented new and useful Improvements in Display-Stands, of which the following is a specification.

This invention relates to sweat pad racks and it consists in the novel features herein- 10 after described and claimed.

An object of the invention is to provide a rack especially adapted to hold harness pads of the character indicated in such manner that the said pads are exhibited or exposed at 15 their edge portions and at the same time the pads are accessible and may be readily removed from the rack. The parts of the rack are so assembled that the pads are supported or held in tiers and in actual practice the rack will contain when filled one 20 gross of pads.

With the above object in view, the rack comprises a base mounted upon caster wheels and supporting a standard. Two 25 sets of arms are journaled upon the standard and are held in spaced relation by means of connecting rods. A bottom plate is located upon the lowermost set of rods and it is upon this plate that the pads are piled.

In the accompanying drawings—Figure 1 is a side elevation of the rack. Fig. 2 is a 30 top plan view of the same. Fig. 3 is a top plan view of a portion of the bottom of the same with parts broken away. Fig. 4 is a 35 detailed sectional view of the intermediate portion of the top of the rack. Fig. 5 is an enlarged plan of the intermediate portion of the top of the rack.

The rack comprises a base 1 which is 40 mounted upon caster wheels 2. A standard 3 is mounted upon the base 1 and the said standard is preferably in the form of a pipe or hollow member. A nut 4 is screw threaded upon the upper portion of the standard 3 45 and a nut 5 is also screw threaded upon the upper portion of the said standard above the nut 4. Arms 6 are journaled upon the upper portion of the standard 3 between the nuts 4 and 5 and the said arms are arranged 50 in cruciform relation with respect to each other. At their outer ends, the arms 6 are provided with diverging branches 7. One of the arms 6 is provided with an offset intermediate portion 8 which receives the 55 other arms 6 and securing bolts 9 pass transversely through the overlapping portions of

the said arms. Arms 10 are journaled for rotation upon the intermediate portion of the standard 3 and the said arms 10 are arranged in cruciform relation with respect 60 to each other. The arms 10 are provided at their ends with diverging branches 11. If desired, the arms 10 may be secured together by bolts similar to the bolts 9 hereinbefore described. Vertically disposed rods 65 12 connect the arms 6 at their ends with the ends of the arms 10 and vertically disposed rods 13 connect the ends of the branches 7 with the ends of the branches 11. All of the said rods 12 and 13 are parallel or approxi- 70 mately so. Bars 14 are secured to the ends of the arms 10 and are disposed at right angles with relation to the said arms. Bars 15 are secured to the ends of the branches 11 and are disposed in parallel relation to the 75 bars 14. A bottom plate 16 lies upon the arms 10, the branches 11 and the bars 14 and 15 and serves as a support for the pads.

In practice, the pads are arranged in piles and these piles are positioned upon 80 the plate 16 between the rods 12 and 13 so that the pads are arranged in tiers and an edge portion of each pad is exposed. In view of the fact that the arms 6 and 10 are rotatably mounted upon the standard 3, the 85 support for the pad may be turned to bring any particular pile of pads in front of an observer.

The parts are so assembled that they may 90 be readily disconnected for storage or transportation and when in knocked down condition, they occupy but small space. Therefore it will be seen that a rack of simple structure is provided especially adapted to be used for holding harness sweat pads. Furthermore, the rack is so constructed that 95 any particular pad may be readily observed or inspected and any particular pad may be easily and quickly withdrawn from the pile of pads in which it may be located.

Having described the invention what is 100 claimed is:

In a device of the kind described in combination, a flat bottom plate arranged to provide rectangular projecting portions at 105 right angles to one another, a base, a rigid vertical standard secured at its lower end to said base, a pair of upstanding rods of equal length secured between the ends of and along the longitudinal edge of each of said 110 rectangular projections, the upper end of said rigid rod being threaded, a nut secured

upon said threaded portion, a pair of arms crossing each other at the upper end of said rigid rod, one of said arms having a central opening through which the threaded portion projects, said mentioned arm resting upon said nut, the other arm being offset over the first arm, means engaging said rod to clamp the two arms together in crossed relation, each of said arms being provided at its outer end with diverging branch arms, a plurality of upright rods connecting said

plate and each of said arms at the points where said branch arms begin to diverge therefrom, the branch arms being secured to the upstanding rods and extending entirely 15 across said rectangular projections.

In testimony whereof I affix my signature in presence of two witnesses.

SIMPSON B. DYER.
